United States Patent Office.

STEPHEN C. MENDENHALL, OF RICHMOND, INDIANA.

Letters Patent No. 70,877, dated November 12, 1867.

IMPROVEMENT IN HAND-LOOMS.

The Schedule referred to in these Letters Patent and making part of the same.

TO ALL WHOM IT MAY CONCERN:

Be it known that I, STEPHEN C. MENDENHALL, of Richmond, county of Wayne, and State of Indiana, have invented a new and useful Improvement in Looms; and I do hereby declare the following to be a full, clear, and exact description thereof, reference being had to the accompanying drawings, making part of this specification, in which—

Figure 1 represents a perspective view of the loom.

Figure 2 is a side elevation of same.

Figure 3 is a side elevation of pulley D.

The same letters of reference where they occur in the drawings denote identical parts.

My invention consists mainly of an improvement in the mode of driving the treadle cam-shaft A and batten Q by means of an endless belt or chain, B.

The treadle cam-shaft A, which is journaled horizontally a suitable distance in rear of the heddle-frame, is rotated by an endless chain or belt, B, extending from the driver D to a spurred pulley or sprocket, C, on the right end of the cam-shaft, to enable the operator to stand square with and facing the front of the machine, and to afford a crank motion on the plane parallel to the motion of the batten, and so that the crank shall be at its most effective position when the batten is in the act of striking up the woof-thread. I have provided a driving-spurred pulley or sprocket, D, and have connected the same to a similar sprocket, C, on the cam-shaft, by means of an endless belt, B, having metallic eyelets. The winch or hand-crank D' is affixed at such position to the sprocket D, and the sprockets C and D are so connected by pitman P to the batten Q as to bring the winch D' and the pitmen P P all or near their dead-points, and with the weight of the operator bearing upon the winch D, so as to concentrate the greatest force at this special and important juncture of the operation, enabling the operator to lay up the woof-thread firmly, and insuring a dense and heavy fabric without the necessity of fulling. The eyeleted belt B b may be formed of canvas or leather, with metallic eyelets, or may be simply a metallic chain. The essential requisites of said belt are pliability without extensibility, and the faculty of communicating positive motion from pulley to pulley.

Fig. 3 shows the mode of attaching the driving-spurred pulley D to the frame of the loom by means of the plate S, which may be secured in its plate by bolts or screws. The slot *u* in said plate is for the purpose of altering the position of the pulley D in order to tighten or loosen the chain or belt B, as may be necessary in the practical working of the machine. The pulley D is supported on a pin or wrist, *f*, working in slot *u*, and secured firmly in its place by means of the set-screw *i*. Another and peculiar feature of plate S is that its position on the frame may be reversed, so as to place the slot *u* several inches lower relatively to the frame of the loom, and thereby accommodate the height of the crank to the height of the operator. This is an important feature of the invention, since it affords a ready means of accommodating the use of the loom either to grown-up persons or children.

What I claim, and desire to secure by Letters Patent, is—

1. The application to hand-looms of the endless metal-eyed belt or metallic chain B b, in combination with the spurred pulleys C and D, the whole being arranged and combined for the purpose of driving the cam-shaft A.
2. The described arrangement of endless metal-eyed belt or metallic chain B b, spurred pulleys C and D, pitmen P P and batten Q.
3. The described arrangement of the endless metal-eyed belt or metallic chain B b, spurred pulleys C and D, pitmen P P, and batten Q, and the crank D', when said crank has such a position on its pulley as to give and time the motions of the batten, and the cam-shaft, as and for the purposes set forth.
4. I claim the reversible plate S, with its slot *u*, or its equivalent, for the purposes set forth and described.

In testimony whereof I have signed my name to this specification in the presence of two subscribing witnesses.

STEPHEN C. MENDENHALL.
